A. J. ADAMSON,
SHOE,
APPLICATION FILED MAR. 31, 1919.

Patented Feb. 15, 1921.

INVENTOR.

A. J. Adamson

BY

Knight Cook

ATTORNEY.

UNITED STATES PATENT OFFICE.

ANDREW J. ADAMSON, OF ST. LOUIS, MISSOURI.

SHOE.

1,368,595.

Specification of Letters Patent. Patented Feb. 15, 1921.

Application filed March 31, 1919. Serial No. 286,436.

To all whom it may concern:

Be it known that I, ANDREW J. ADAMSON, a citizen of the United States of America, a resident of the city of St. Louis, in the

5 State of Missouri, have invented certain new and useful Improvements in Shoes, of which the following is a full, clear, and exact description, reference being had to the accompanying drawings, forming a part 10 of this specification.

My invention relates to a shoe for human wear, having an arch therein above the arch of the main sole and adjacent the outer side of the shoe, whereby the foot of the 15 wearer of said shoe is directed laterally toward the inner side of the shoe, causing the weight of a person's body to be thrown inwardly toward the inner side of the shoe and onto the great toe and the portion of 20 the foot immediately in the rear of the great toe, instead of upon the outer fleshy part of the foot. By forming an arch in a shoe adjacent the outer side of the shoe, as above mentioned, the weight of a person 25 wearing the shoe is not only thrown inwardly to the inner side of the shoe but is also held in such position, with the result of avoiding friction between the foot and the shoe, due to rolling of the foot with- 30 in the shoe, which occurs in shoes of the ordinary type in the use of which the foot is free to move from side to side. Furthermore, in the use of a shoe having an arch 35 therein as contemplated by my invention, the foot of the wearer, constantly directed toward the inner side of the shoe toward the great toe, there is a natural and constant tendency to cause all of the toes of the foot to be moved toward the inner side of 40 the shoe, which results in the toes being spread out into their natural positions, with avoidance of any cramping of the toes, or the bending of the smaller toes under each other, with consequent discomfort and ill 45 effects, such as corns and misshapen toes.

Figure I is a side elevation of a shoe made in accordance with my invention, a portion of the shoe upper being broken out to show the arch within the shoe.

50 Fig. II is a plan view of the inner sole and arch of my shoe.

Fig. III is a vertical cross section taken on line III—III, Fig. I.

In the drawings, I have shown a shoe for 55 the left foot of a wearer, and it is to be understood that an arch similar to that shown

in this shoe would be located in a shoe for the wearer's right foot in a position directly the reverse of the position of the arch in the shoe for the left foot.

60

My shoe comprises the usual main sole 1, and the usual upper 2. The main sole of the shoe is surmounted by an arch A comprising an inner sole 3, between which and the main sole is interposed a filler 4, which is located 65 above the arch portion of the main sole. This filler tapers gradually forwardly and backwardly from its crown lengthwise of the arch of the main sole, and also tapers gradually from the outer side X of the shoe 70 to the inner side Y of the shoe, the thickest portion of the filler being at the outer side X.

At the outer side of the arch A, and constituting a portion of said arch, is a stay or 75 upturned lip 5 from which the arch A is inclined laterally toward the inner side of the shoe, with a gradual taper which causes the foot of the wearer to constantly assume an immovable position between the stay and 80 the inner side of the shoe.

The presence of the arch A at the outer side of a shoe, as contemplated by my invention, is of particular merit and has many advantageous benefits. By the location of 85 the arch A within the shoe, at the outer side of the shoe, the foot cavity at such outer side is reduced and the height of the cavity at the inner side of the shoe is larger than that at outer side of the shoe, hence, the 90 wearer's foot is constantly directed toward the inner side of the shoe without any tendency of the foot to move in any direction, either with rolling or sliding motion. There is therefore, no opportunity for the creation 95 of friction between the sole of the foot and the in-sole of the shoe, but instead, a constant tendency to retain the inner side of the foot against the inner side of the shoe, which results in the foot being spread into a natural 100 position, and the toes of the foot being constantly separated, with no opportunity of their being cramped or turned under each other, as is possible in the ordinary shoe.

Furthermore, the arch in my shoe obviates 105 any tendency on the part of the wearer of the shoe to turn the shoe outwardly with consequent excessive wear or over-running of the heel. The shoe therefore, necessarily retains its original shape.

110 In the use of my shoe, the weight of the wearer's body is disposed entirely upon the

arch of the foot and the remainder of the foot in front, and at the rear of the arch, including the great toe, the outer fleshy portion of the foot serving only as a cushion, and preventing jarring of the wearer's body.

In the use of a shoe constructed in accordance with my invention, there is, as previously explained, no opportunity for friction between the foot and the sole of the shoe, hence, perspiration of the foot, due to frictional engagement with the shoe is avoided, and bad odors resulting from perspiration are consequently eliminated.

Furthermore, the avoidance of friction obviates wear upon hosiery, which occurs constantly in shoes constructed in the ordinary manner.

While I have described my invention as incorporated in a shoe, it is evident that it is equally adaptable to boots, and therefore, while the invention is claimed as relating to a shoe, it is to be understood that protection therefore extends to boots.

I claim:

1. A shoe having an arch built integrally therein at its outer side directly above the arch of the main sole.
2. A shoe having an arch built integrally therein at its outer side, said arch tapering toward the inner side of the shoe.
3. A shoe having an internal arch at its outer side directly above the arch built integrally therein of the main sole, said internal arch extending forwardly and rearwardly above the arch of the main sole and being tapered toward the inner side of the shoe.
4. A shoe having an internal arch built integrally therein at its outer side directly above the arch of the main sole, said internal arch extending longitudinally of the shoe and also being inclined toward the inner side of the shoe, and a stay at the outer side of said internal arch.

In testimony that I claim the foregoing I hereunto affix my signature.

ANDREW J. ADAMSON.
